UNITED STATES PATENT OFFICE

122,610

DESIGN FOR A PORTABLE GRANDSTAND FRAME

Reinhold A. Uecker and David E. Beatty, Wauwau-tosa, and Lawrence C. Oertle, Milwaukee, Wis., assignors to Safway Steel Scaffolds Co. of Wisconsin, Wauwau-tosa, Wis., a corporation of Wisconsin

Application February 7, 1940, Serial No. 90,077

Term of patent 14 years

To all whom it may concern:

Be it known that we, Reinhold A. Uecker,
David E. Beatty, and Lawrence C. Oertle, citizens of the United States of America and residents of Wauwau-tosa, Wauwau-tosa, and Milwaukee, respectively, in the county of Milwaukee and State of Wisconsin, have invented a new, original, and ornamental Design for Portable Grandstand Frame, of which the following is a specification, reference being had to the accompanying drawing, forming a part thereof.

In the drawing:

The single figure shows a perspective view of the portable grandstand frame showing our new design.

We claim:

The ornamental design for a portable grandstand frame as shown.

REINHOLD A. UECKER.
DAVID E. BEATTY.
LAWRENCE C. OERTLE.
